UNITED STATES PATENT OFFICE

2,457,242

GUN TURRET

Cutler D. Knowlton, Rockport, Mass., assignor to
 United Shoe Machinery Corporation, Flemington, N. J., a corporation of New Jersey

Application November 30, 1944, Serial No. 565,939

10 Claims. (Cl. 89—41)

1

My invention relates to turrets upon which guns are mounted and which protect the ammunition, various operating and controlling instrumentalities and the gun-crew. More particularly is the invention directed to organizations in which the guns are directed for their discharge, both in azimuth and in elevation, by movement of the turret.

The invention has as an object the provision of such a turret which is relatively inexpensive to construct; which offers high resistance to injury preventing operation; which furnishes a convenient mounting for the guns; which so disposes the gunner and sight that they are in a relation for ready direction of the gun upon the target; and which maintains the gun-crew free from interference by objects movable within the turret.

In the attainment of this object, there is rotatable upon a base, either fixed or mobile, a table carrying pairs of spaced rolls rotatable about horizontal axes and with the pairs spaced from each other. These rolls support rotatably a drum furnishing the turret upon which a gun or guns are mounted. The drum, with its circumferential wall and opposite heads, is constructed readily, and the form is such as to tend to deflect shells discharged against it. The vertical heads of the drum, unobstructed by any supporting means, give an effective mounting for guns and permit the delivery of ammunition to them without interference. The pairs of rolls preferably carried by shafts journaled in spaced pairs of pedestals rising from the table, motors for rotating the shafts being located within and protected by the pedestals. These pairs of pedestals and rolls are so spaced that the power of the motors is effectively applied to rotate the drum in elevation. To aid in the retention of the drum in operating position, one of the supporting rolls may be provided with a groove receiving a circumferential projection from the drum. The other rolls preferably present ungrooved surfaces upon which the drum-projections rest and may move laterally. This allows the driving of the drum by the rolls, even if it is deformed in action. There is shown protected gearing for rotating the drum-supporting table in azimuth by a motor upon the table, means for securing the drum against rotation upon the rolls during transportation of the turret, and means for turning both the table and drum manually, as in connection with repair-work.

The invention further provides a comfortable seat and head-rest for the gunner, which keep

2

his eye in correct relation to the sight during the rotation of the drum, the seat also furnishing a support while he is scanning; means for selectively charging any one of a plurality of guns upon the turret and for utilizing a portion of the charging means for furnishing emergency pressure to the motors through which the turret is operated; means by which a second man of the crew may control the motors instead of, or to assist, the gunner, also means whereby he may shift the sight to introduce a lead-correction; and an effective system of ammunition-supply for the guns.

In the accompanying drawings illustrating a particular form of my invention,

Fig. 1 shows the turret in side elevation;

Fig. 2 is a similar view, with a side wall of the turret removed and parts broken away;

Fig. 3, an enlarged side elevation of a portion of the ammunition-supplying means;

Fig. 4, a front elevation of the turret with the front of the cylindrical wall broken away, parts being omitted;

Fig. 5, an irregular transverse section through the driving mechanism for the turret, viewed from the front;

Fig. 6, a broken top plan view of the mechanism for turning the turret in azimuth;

Fig. 7, a broken side elevation of one of the mechanisms by which the turret is turned in elevation;

Fig. 8, a sectional detail on the line VIII—VIII of Fig. 7;

Fig. 9, a similar view on the line IX—IX of Fig. 7;

Fig. 10, an enlarged sectional detail of the retaining means for the hand-crank of Fig. 9;

Fig. 11, an enlarged detail, partly in elevation and partly in section, of one of the table-supporting rolls;

Fig. 12, a broken top plan view of the treadle-operated pump;

Fig. 13, a side elevation of the gunner's chair and head-rest;

Fig. 14, a front elevation thereof;

Fig. 15, a sectional detail on the line XV—XV of Fig. 14;

Fig. 16, a side elevation of the lead-controlling connections for the sight;

Fig. 17, a like view, especially illustrating the means for mounting and charging the guns;

Fig. 18, an enlarged view, partly in side elevation and partly in vertical section, of the rear gun-mounting;

Fig. 19, a section on the line XIX—XIX of Fig. 18;

Fig. 27, a front elevation of the gunner's sight and its mounting;

Fig. 28, an enlarged section on the line XXVIII—XXVIII of Fig. 27, with the sight removed from the mounting;

Fig. 29, a detail in side elevation of the connections for the second man's lead-control, taken from the right of Fig. 28;

Fig. 30, a broken sectional detail of the azimuth-locking plunger for the sight;

Fig. 31, a top plan view of the sight and the second man's control; and

Fig. 32, a perspective, especially showing the ammunition-supplying system, looking downwardly from the rear of the turret.

Upon the horizontal top of a base 10, which may be fixed in position or mounted for transportation, is secured a ring 12 (Fig. 2), about the periphery of which are gear-teeth 14, partly formed in an upwardly extending flange 16 of the ring. Within the flange, the ring has a horizontal surface 18 furnishing a track on which turns a table 19, having opposite extensions 20, 20. This table is stayed by inverted T-beams 21, 21 (Fig. 11), welded to it and running across its sides and along opposite sides of the extensions. The table is supported upon the track by frusto-conical rolls 22, of which there may be four, separated from one another by 90°. Each roll is rotatable about a spindle 24 extending between the depending arms of a bracket 26, passing up through openings in the table-top and secured thereto by screws 28. The spindle is so inclined in the bracket-arms that the under-side of the roll is horizontal to correspond to the surface of the track. The contour of the outer end of each roll at 30 is such that it makes full contact with the inner side of the flange 16, to provide a bearing surface of considerable area holding the table against lateral displacement upon the base. Play may be taken up at these areas of contact by outward adjustment of three of the brackets 26. For this purpose the screws 28 may pass through openings 32 in the body of the bracket elongated radially of the table. With these screws loosened for any of the rolls, said roll may be shifted outwardly by an inclined push-screw 34, threaded through a depending outer flange 36 upon the bracket and engaging a shoulder 38 on the table-top. A protective skirt 40 is welded to the edge of the table, extending below the plane of the gear 14, and from this skirt directly adjacent to the gear, a horizontal flange 42 is attached and projects below the gear. Between the flange and the ring 12, a packing strip 43 may be interposed to exclude dust from the rolls, track and gearing. The large opening at the center of the ring 12 is closed by a frusto-conical plate 45 and a casing 47 which it supports, the casing containing a collector

device C through which connections for the various electrical devices of the turret are carried.

Rising from the extensions 20, 20 of the table, and being upwardly and outwardly inclined, are two pairs of hollow pedestals 44, 46, the pedestals of each pair being spaced from each other transversely of its extension and the pedestal 44 being the wider of the pair. Each pedestal near its upper extremity carries bearings 48, and in these bearings of each pair of pedestals is rotatable a horizontal shaft 50 (Figs. 5, 7 and 9). Within each pedestal a roll is fastened to the corresponding shaft. Three of these rolls, as that designated as 52 in Fig. 5, have cylindrical peripheries, while the fourth roll 54 is grooved. Upon these rolls, at each side of the table, rest circumferential projections or tires 56, 56 at the opposite sides of the turret-proper T. The grooved roll retains the turret against displacement upon its support, while the fact that the other rolls have no lateral restraining effect allows the rotation of the turret to continue, even if it has become considerably deformed in action.

The turret is in the form of a drum having a cylindrical wall 58 (Fig. 2) and opposite vertical walls or heads 60, 60, these walls being welded together, and the tires welded to both the cylinder and the heads. Access is had to the interior of the turret and the occupants given an opportunity for scanning, by an opening at the top of the turret in an upward extension 62 from the side and circumferential walls. The opening may be wholly or partially closed by three covers. One, designated as 64, is hinged at the rear and manipulated through an arm 66 extending from it downwardly and rearwardly (Fig. 2), and latched up, when desired, by a spring-plunger 67. Two forward covers 68, 68 are hinged at opposite sides and have upon their upper faces handles 69 by which they may be thrown back. There is an opening 70 in the front wall of the extension 62, and at the rear of this opening is mounted the sight S, which directs the fire of guns G carried by the vertical walls of the turret. The support of the tires upon the rolls permits the turret to turn on the table to different angular positions in a vertical plane, thus providing for variation in elevation of the guns, while the rotation of the table 19 on the base 10 allows for changes of the guns in azimuth. Two guns, as shown in Fig. 1, are carried on each of the heads 60 by a shield or housing 71 attached to the outer face of the head over a large opening therein, it forming, in effect, a portion of said head.

In elevation, the turret is turned by frictional engagement of the supporting rolls 52, 54 with the tires. The roll-shafts 50 are driven by hydraulic mechanism and connecting gearing situated within the wider pedestals 44. It is to be noted that the separation between the rolls of the supporting pairs at each side of the turret bears such a relation to the diameter of said turret, that the center of rotation is low, the tires running in proximity to the top of the table 19. This increases the stability of the mounting and the driving effect of the rolls upon the turret, the latter because of the large horizontal component of the turret-weight acting against the rolls. It may be desired to secure the turret T against rotation upon its supporting rolls, as when it is to be transported. For this purpose, there is mounted on the outer wall of each of the pedestals 44 and 46 a plate 72 (Figs. 1 and 7), arranged for movement toward and from the turret by virtue of its attachment to the pedestal

by screws 74 passing through slots 75, which lie in a substantially radial direction with respect to the turret. Angular ends 76 of the plates extend over the inner circumference of the tires 56, where they project beyond the heads 60 of the turret. Into clamping engagement with the tires, the plate-ends may be drawn by pull-screws 77, turning in lugs 78 upon the pedestals and threaded into lugs 79 on the plate. Normally, the screws are adjusted to position the plate-ends out of contact with the tires. But when the turret is to be fixed against rotation upon its rolls, with the screws 74 loosened the screws 77 are turned to force the plate-ends against the tires, after which the screws 74 are tightened.

The means for turning the table 19, and with it the turret T, about a vertical axis is shown in Figs. 5 and 6. Meshing with the gear 14 is a pinion 80 fast upon a vertical shaft 82, rotatable in bearings upon the forward extension 20 of the table. On the upper extremity of this shaft within a housing 84, a worm-wheel 86 is secured, this meshing with a worm 88 fixed to a horizontal shaft 90 rotatable in a bracket 92 attached to the top of the table. At 94, the shaft 90 is joined to the shaft of an hydraulic motor 96, mounted upon the housing 84. This motor, and others to be described later, receive pressure from a pump 98 (Fig. 2) driven by an electric motor and exhausting to a tank 100. These elements are contained in a housing 102 upon the extension 20 at the rear of the table. The hydraulic mechanism is not a part of the present invention and need not be described in detail. Upon such occasions as when repairs are being made, it may be desired to rotate the table 19 manually. For this purpose, the shaft 90 carries a pinion 104, and there may be brought into engagement with this a pinion 106 on the elongated shaft of a hand-crank 108. The inner end of this crank-shaft may be inserted in a bracket 110 upon the housing 84, and then the pinion 106 lowered into mesh with the pinion 104, the outer portion of the shaft entering a groove in a bracket 112 attached to the housing. In this bracket the shaft may be retained temporarily by a cotter-pin. Collars 114, 116 upon the shaft contact with the brackets to determine the meshing of the pinions. Rotation of the crank will, through the gearing 106, 104, 88, 86, 80 and 14, 50 turn the table and, therefore, the turret in azimuth.

For the rotation of the turret in elevation, power is applied simultaneously to the tires 56, 55 by driving mechanisms contained in the diagonally disposed pedestals 44, 44. These mechanisms are of the same character, and but one need be described. Referring to Figs. 5, 7, 8 and 9, each shaft 50 has secured to it within the pedestal a gear 120, meshing with a pinion 122 on a counter-shaft 124 journaled in the casing. A gear 126 on this counter-shaft is driven by a pinion 128 on the shaft of an hydraulic motor 130, attached to the pedestal. The motors for both shafts 50 are driven by the pump 98, previously mentioned. To allow each of the motors 130 to be adjusted vertically to establish the correct relation of the pinion 128 to the gear 126, as appears in Fig. 9, the motor extends through an opening 132 in a wall of the pedestal 44 and in a spacer 134, and is secured to a plate 136, which is attached by screws 138 to the pedestal-wall. The screws fit openings in the spacer and pass through vertical slots 140 in the plate 136 (Fig. 8). On loosening the screws, the

plate, and the motor 130 which it carries, may be adjusted vertically, as desired. Manual rotation of the turret in elevation may be effected through a hand-crank 142, geared to the gear 126 of one of the two driving mechanisms. Mounted in the corresponding pedestal 44 is a horizontal tube 144, within the outer end of which is a bearing sleeve 146. There may be inserted through this sleeve a shaft 148 of the crank 142, this shaft having a reduced end on which is a pinion 150, of such diameter that it will pass through the sleeve and come into mesh with the gear 126. When such meshing has been established, the shaft may be maintained in the proper longitudinal position by a spring-actuated latch-pin 152 (Fig. 10), engaging the inner end of the sleeve when the hub of the crank contacts with the outer end. By this crank, the turret may be turned to the desired position about its horizontal axis. An inclined surface 154 upon the inner end of the sleeve engages the latch, causing this to yield when the crank is to be removed.

There appears in Fig. 2 means for limiting the elevational travel of the turret in both directions, 25 so this may not pass the desired angle. When the movement is clockwise, a cam-plate 156 acts on a lever 158, fulcrumed on the forward table-extension 20, to gradually close a valve 157 controlling the hydraulic pressure to the motors 120 and finally to shut off such pressure. For movement in the opposite direction, a cam-plate 159 engages the same lever to produce the same effect. Should this control fail, wedges 160, 162 fixed to 30 the tires 56 engage the supporting rolls 52 to stop positively movement in both directions.

In event of the pump 98 or its motor failing, means is provided whereby the occupants of the turret may still operate the hydraulic motors 86 and 130 to turn the table 19 and the drum T thereon, and, as will hereinafter appear, perform another operation, using in part the same mechanism. Extending across the lower portion of the drum is a spindle 164 (Figs. 2, 4 and 12), about 45 which two sleeves 166, 168 may turn. Fixed to each sleeve is a depending arm 168, terminating in a loop 170 forming a treadle. Attached to each arm 168 is a block 172, to which is pivoted the rod 174 of the plunger of a force-pump 176 mounted upon the wall 58 of the turret. Each treadle-arm and its pump-plunger is retracted by a tension-spring 178 connecting the arm to a wall 60 of the turret. By disconnecting the pump 98 from the hydraulic motors and working the treadle-arms, sufficient pressure may be applied to the motors to turn the table and the drum.

The turret accommodates two men to control the hydraulic mechanism which turns the table 19 and the drum T, to direct the fire of the guns G, and to operate and service said guns. The gunner occupies a chair C, which is arranged for ready movement between two positions, respectively, for scanning and firing. This chair is best shown in Figs. 2, 13, 14 and 15 of the drawings. 60 Extending across the turret between the turret-walls 60, 60 is a lower bracket 180, and projecting from one of said walls is an upper bracket 182. Attached to these brackets is the back 184 of the chair. Guided for movement between the brackets and cleats 186 attached to them is a slide 188, on the angular lower extremity of which is fastened a seat 190 for the chair. Supported at its ends in the brackets adjacent to one of the walls 60 is a stationary screw 192, and surrounding the screw is a hand-nut 194. From a vertical

carrier-plate 196, lugs 198, 198 extend above and below the nut, so rotation of the nut will raise and lower the plate. The inner edge of the plate, or that opposite the lugs, is guided between the chair-back 184 and the slide 188. Rotatable upon the plate at the rear is a shaft 200 provided with a forwardly projecting arm 202, having at its outer end a handle 204 convenient for manipulation by the occupant of the chair. Depending from the inner end of the shaft 200 is an arm 206, on the forward side of which is a latching projection 207. This projection extends through a longitudinal slot 208 in a rear vertical section 209 of the slide, and may enter either a lower opening 210 or an upper opening 212 in the body of the slide. When one of the openings registers with the projection, said projection is caused to enter it by an expansion-spring 214 bearing against the arm 206 and contained in a recess in a bracket 216 fixed to the plate 196. By engagement of the ends of the slot 208 with the projection 207, which is maintained in the slot by the contact of the arm 206 with the bracket, the movement of the slide 188 in opposite directions is limited. A tension-spring 220, extending between the bracket 182 and the lower portion of the slide, exerts its force to carry the seat to its highest position, the weight of the occupant upon the seat lowering it. In the first of these two positions, with the latching projection 207 in the slide-opening 210, the gunner will be so elevated and held that his head will project through the opening in the turret-extension 62 for scanning. When he wishes to fire the guns G at objects observed, he depresses the handle 204 withdrawing the projection from the opening 210. His weight lowers the slide and seat until the latching projection enters the slide-opening 212. The eyes of the gunner are now opposite the sight S, by means of which he may direct the fire of the guns. Another depression of the handle 204, and the relieving of the seat of the gunner's weight will allow the spring 220 to restore said seat to the scanning position. To best locate the seat for the height of the gunner, the nut 194 may be turned. This will alter the vertical relation of the latching projection 207, and consequently that of the seat and of the occupant's eyes.

That the gunner's head may be best disposed with relation to the sight S, an adjustable head-rest 222 (Figs. 13 and 14) is associated with the chair C. Rotatable in bearings upon the bracket 182 is a shaft 224, to which are secured two arms 226, 226, each of which has an upward extension 228 containing two longitudinal slots 230. Projecting rearwardly from each side of the head-rest is a wall 232, in which is an upper opening 234 and a lower slot 236, formed as an arc about said opening. The walls are secured to the arm-extensions by bolts 238, 238, passing, respectively, through the upper slot 230 and the opening 234 and the lower slot 230 and the slot 236. It will be seen that, by shifting the rest-walls upon the arm-extensions, both the height of the rest and its angle upon the bracket 182 may be varied and then maintained by tightening the bolts. The rest may thus be adapted to meet the needs of the gunner. To place the eye of the gunner in the best relation to the sight S, the rest would be too far forward from its normal or scanning relation, when arranged for firing, for comfort at other times. To permit the angle of the rest to be altered quickly and maintained as desired, there is fastened on the shaft 224 an arm 240, situated adjacent to one of the turret-walls 60.

Extending rearwardly from the upper end of the arm is a toothed segment 242. A tension-spring 244, joining the segment to the wall, tends to draw the rest forward to an angle limited by the engagement of an extension 245 from the arm with the bracket 182. A latching lever 246, fulcrumed upon a bracket 248 fixed to the turret-wall, has a toothed end forced into engagement with the teeth of the segment by an expansion-spring 250 interposed between the bracket and the lever. A handle 252 on the forward end of the lever permits the gunner to free the segment, and then, by backward pressure of his head or the forward pull of the spring, cause or allow the rest to assume the most convenient position for the existing conditions.

A chair for the second man is shown in Fig. 2 as consisting of a plate 260, attached at 262, 262 to the curved wall of the turret at the rear. At 264 the plate extends forwardly to furnish a seat, and the upper portion is curved to provide a head-rest 266. This chair is used during the operation of the treadles 170 and the handling of ammunition. A seat 268, which the second man may use while scanning (Fig. 4), is pivoted at 269 to a vertical guide-bar 270 attached to the right-hand wall 60 above the chair 260. Pivoted to one extremity of the seat 268 and at the opposite end to a slide 271 movable along the bar is a brace 272. Carried by the slide is a spring-plunger 274, which may engage a depression in the bar to hold the seat in a horizontal position, ready to be occupied. The brace may be freed by withdrawing the plunger and the seat allowed to collapse to its idle relation parallel to the turret-wall.

For mounting each of the two guns G in each of the turret-housings 71, the same means may be employed, this not only carrying the gun in a normally fixed relation, but also permitting said gun to be bore-sighted, or arranged in the correct horizontal and vertical angles to correspond to the sight S. Referring to Figs. 1 and 17 to 23, each gun is carried in a cradle 276, at the underside of the forward extremity of which the yoked head 277 of a spindle 278 is pivoted. The spindle passes loosely through a sleeve 279 threaded into a vertical opening in a horizontal extension of the housing 71. On the sleeve is a lock-nut 280 for engagement with the housing-extension. When the sleeve is rotated, by an enlargement 281 upon its upper end on which the head of the spindle rests, it will either raise the forward end of the cradle or allow it to descend, the muzzle of the gun moving similarly. To the cradle near the rear is connected means for permitting the vertical movement just described, and also for adjusting the gun-muzzle horizontally. Pivoted at 282 about an axis extending transversely of the gun between lugs 284, 284, depending from the cradle, is a block 286 having opposite trunnions 288, 288, the axis of which lies longitudinally of the gun. On these trunnions hang a pair of plates 290, 290, at the inner sides of which are shoulders 292 and which are secured to each other by bolts 294, 294. The shoulders support a headed shank 296, passing through an opening between the plates and having, below these, a horizontal transverse extension 298 provided at its outer ends with conical recesses 300, 300. The shank 296 furnishes a pivot for the extension at right angles to the pivots at 282. Into these recesses fit the ends of screws 302, 302 threaded through lugs 304, 304 upon the housing. Opposite rotation of the screws 302 swings the muzzle of the gun horizontally, the rotation

of the spindle 278 in the sleeve 279 and of the shank 296 and its extension upon the plate-shoulders 292 permitting this. When the muzzle is moved vertically by adjustment of the sleeve 279, the rear of the cradle may rise and fall by virtue of the pivoting of the cradle-lugs 284 at 282 and of the extension 298 upon the screws 302. Movement of the plates 296, 290 about the trunnions 288 prevents cramping during this vertical adjustment, if the axes of the pivotal connections at 282 and 302 do not lie in parallel planes.

In the discharge of the guns, they may fail to recoil normally to produce the succeeding loading and firing cycle. In such event, the treadles 170, which have already been described as employed to operate to the auxiliary pump 176, may be used to charge any of the guns which may have jammed, said treadles being actuated by the second man to draw back the breech-bolt of the gun in the direction of recoil. Each of the 15 treadles is utilized for charging the guns at that side of the turret, and there is means for selectively connecting the treadle to the gun to be charged. As appears in Figs. 2, 17 and 20, each of the sleeves 166 is joined by an arm 308 and a link 310 to one arm of a bell-crank-lever 312, fulcrumed upon the inside of the corresponding 20 turret-wall 60. To the second arm of the lever is connected a vertical bar 314, pivoted to an inner arm 316 of each of two bell-crank-levers 316 fulcrumed upon the inner wall of the housing 71, above the respective guns. Each lever 316 has a second arm 320, there being an intermediate 25 tubular hub. The length of this hub differs, because the lower guns are farther out from the 30 turret-wall. Each of the arms 320 has at its outer side a longitudinal recess, in which is an arm 322 fast upon a spindle 324 turning in the hub. An expansion-spring 326 normally forces the arm 322 against the inner wall of the recess, and the 35 inner end of the spindle projected through the lever 316 to provide a finger-piece 328. Because of the lengths of the lever-hubs, the arrangement of the spring 326 is different at the upper 40 and lower guns, though the action is the same in each case. As illustrated in Fig. 21, the spring of each of the upper guns is between the outer end of the spindle 324 and an abutment 330 furnishing a portion of the housing 71. Fig. 22 shows the spring for one of the lower guns, as 45 interposed between an enlarged finger-piece 332 at the end of the spindle 324 and a shoulder 334 within the long hub of the lever 316. In each case, the arm 322 has a terminal 336 clamped in place by a screw 338, so the vertical position 50 of a horizontal extension 340 of the terminal may be adjusted with respect to a hook 342 on the breech-bolt of the corresponding gun (Fig. 23). The extension 340 has an arcuate surface 344, which is hooked oppositely to that of the breech-bolt. Normally the hook 344 lies just inside and 55 clear of the hook 342, as the breech-bolt reciprocates during discharge of the gun. When, however, the finger-piece of the spindle is forced out by the man within the turret, the surface 344 is carried into alignment with the breech-bolt-hook, the spindle-arm 322 still lying within the recess in the arm 320. Now, if the treadle 170 at that side of the turret is swung forward, both the corresponding levers 316 will be turned. The movement of one will be idle, but the other, the finger-piece of which has been actuated, will turn the arcuate surface 344 downwardly and 60 rearwardly against the hook 342, imparting to the breech-bolt its movement of recoil. The in-

terengagement of the hooked members will, during this action, be maintained independently of pressure upon the finger-piece. This will continue until the breech-bolt has reached the point of full recoil. As the active lever 316 travels on to its extreme position, the surface 344 will pass beyond the breech-bolt-hook, freeing itself from this, so the breech-bolt may complete the loading cycle under the influence of its counter-recoil-spring. The lever is returned by the spring 326 to its normal position, with the surface 344 at the inner side of and clear of the hook. The treadle having been retracted by its spring 178, the charging mechanism is ready for another operation.

To direct the fire of the guns G, as determined by the sight S, the gunner controls the movements of the turret in azimuth by varying the time at which the hydraulic motor 96 turns the table 19, together with the rate and direction of the drive, and similarly governs the movement in elevation by the change in the motors 130, 130 which rotate the drum T. The application of pressure to the motors from the pump 98 is under the control of valve mechanism V (Fig. 24), actuated by grip mechanism H having handles 346, 346 grasped by the gunner. Movement of the handles in a horizontal direction causes a corresponding azimuth movement 30 of the guns, while vertical movement produces their elevation or depression. It may be desirable for the second man to have control of the motors, if, for example, the gunner is disabled, or for aiding the gunner by bringing his sight approximately into the field occupied by the target. The means for effecting this is illustrated in Figs. 2, 24, 25 and 26 of the drawings. The mechanisms V and H may be conventional. It is only necessary to say that the handles 346 are attached to a body-portion 348, which may be considered as a primary controlling member and which is mounted to rock horizontally and vertically about pivots 350 and 352, respectively, for the purpose just stated. Auxiliary controlling mechanism H' is carried with the mechanism H on a bracket 354 attached at the front of the turret to the wall 58. In the bracket a horizontal shaft 356 is rotatable, and has fixed to one end, adjacent to the mechanism H, and at the opposite end, blocks 358 and 359, respectively. On the first of these blocks a yoke 360 is pivoted and on the second a yoke 362. These yokes, as to their action upon the primary member 348, may be considered as secondary and tertiary controlling members, respectively. Said yokes are connected to swing together by a link 364. Projecting from the yoke 360 is an arm 366, which is connected through a link 368 and universal joints 370, 370 to the grip-body 348 at one side of its axis of horizontal oscillation. Depending from the yoke 360 is an arm 372, which is united by a link 373 and universal joints 374, 374 to the connections 375 between the grip mechanism H and the valve mechanism V, by which the vertical oscillation of the body is communicated to the valve mechanism. The yoke 362 is situated near one of the walls 60 of the turret, and projecting rearwardly from this yoke, to a point at which it may be grasped by the second man, is a controlling stick 376 (Figs. 2 and 25). The weight of the stick is supported or counterbalanced by a helical spring 378 joining it to the turret-wall. It will be seen that, if the stick is swung laterally, the movement will be transmitted through the yoke 362, link 364, yoke 360 and link 368 to the grip-body, shifting

this in the same direction as though the handles 346 were actuated to produce the azimuth movement of the turret. If the movement of the stick is in a vertical direction, the shaft 356 will be rotated and the yoke 360, the arm 372 and the link 373 will effect the valve-connection 375, as though the handles were moved to change the elevation of the turret. Any movement of the stick having both horizontal and vertical components will similarly shift the body 352 and the valve mechanism to give proportionate movements in azimuth and elevation.

It may be desirable to apply to the sight S a lead-correction, which takes into account the differential in travel between the guns and the target. The means for accomplishing this is provided by the present invention, and is under the control of the second man. As shown in Figs. 16, 27 and 28, the sight S is attached to a segmental slide 386, adjustable in a horizontal segmental yoke 388 and retained in different angular positions by a spring-plunger 390, entering any one of a plurality of depressions 392 in the slide. At one side, the yoke 388 has a trunnion 394 turning in one side of a vertical yoke 396. Opposite trunnions 395, 395, projecting from the top and bottom of the yoke 396, support it upon an upper wall of the turret-extension 62 and on a bracket 397 secured to the turret-wall 52 (Fig. 2). The sight is thus mounted in front of the opening 70 in the turret-extension. At the side of the yoke 396 opposite the trunnion 394, a shaft 398 is rotatable, and projects into the yoke 388 to furnish a second horizontal trunnion. An arm 400 is fixed to the shaft 398, and has a plurality of depressions 402 arranged along an arc, any one of which may receive a spring-plunger 404 carried by the yoke 388. The angular adjustment of the sight horizontally with the slide 386, and its angular adjustment vertically with the yoke 388, these adjustments being maintained by the plungers 390 and 404, respectively, permit the making of coarse or approximate corrections for lead, both in azimuth and in elevation. These approximate adjustments position the sight within the range of the finer correcting mechanism, now to be described.

As the second man follows the tracer-bullets discharged from the guns G, and compares their paths with the position of the target, he may make a more exact lead-correction by moving the sight about the trunnions 394, 398, and 395. Upon the outer extremity of the shaft 398 an arm 406 is secured. Clamped in the outer end of this arm is a rod 408, which is curved rearwardly and upwardly (Figs. 31 and 32), and terminating at a point readily accessible to the second man for the actuation of the sight S. Here, it extends over the surface of a spherical segment 410, the lower edge of which is fixed to a shelf 412 supported at its ends between the turret-walls 60 upon brackets 413. The rod carries a friction member 414 of felt, or the like, contacting with the segment and forced against it by a screw 416, threaded through the rod and upon which the friction member is mounted. Because of the arrangement of the sight to move upon two sets of trunnions in directions at right angles to each other, it has a capacity for universal movement under the influence of the rod, so the sight may be turned in any direction within the required limits, as determined by manipulation of the friction member 414, through paths made up of horizontal and vertical components. The lead may, therefore, be quite exactly determined.

the adjustment at 390, 404 having, if necessary, brought the member 414 to such a position that it will remain upon the surface of the segment 410 during further adjustment. It may be desired to fix the sight in a normal mean position, both in azimuth and in elevation, so no change for lead can be made. This may be in connection with the bore-sighting of the guns or when firing at stationary or slow-moving objects. To permit this, the yoke 396 has at one side of its lower portion a horizontal arcuate surface 418. Movable in a casing 420 carried by the bracket 391 is a spring-plunger 422, urged against the surface 418 to enter a depression 424. This acts to lock the sight in the azimuth. Similarly for the elevational movement, one end of the yoke 396 has a depending arm 426, at the lower end of which is an arcuate surface 428. A depression in this surface receives a spring-plunger 430 movable through the yoke 396, and which in every essential particular may resemble the plunger 422 and its mounting. Either the plunger 422 or 430 may be manipulated by a finger-piece 432, which it carries. Upon the finger-piece is a projection 434 (Fig. 30), which may either enter a slot 436 in the casing, or may be withdrawn, rotated and seated in a depression 438 in the end of the casing. In the first of these positions, the plunger is free to enter the corresponding depression and lock the sight against movement. In the other said plunger is held ineffective, to permit control of the lead, as previously described.

The guns G are supplied with cartridges assembled in belts of the disintegrating link type. The belts are in sections B, each section being stored in a box 440 in the manner illustrated in Fig. 32. In filling a box, the belt is first led from a free end vertically down the inner side of one wall of the box at 442, and then back and forth alternately in opposite directions to furnish layers 444. The boxes for immediate use are placed upon a shelf 446 to supply the upper guns at both sides of the turret and upon a shelf 448 for the lower guns. Each shelf is supported at its ends upon cleats 450, 450 fixed to the walls 60, 60 of the turret, these shelves being at such an angle fore and aft that, when the turret presents the guns horizontally, the boxes are inclined forwardly. The ammunition is, therefore, less liable to displacement from the boxes when the turret rotates rearwardly to elevate the guns to extreme positions. To retain the boxes in place, each shelf has a cleat 452 extending along its rear edge and a cleat 454 along its forward edge. To hold the boxes against tipping rearwardly upon the shelves during the elevation of the guns, each box has along its forward wall near the bottom a horizontal groove, which receives a rib 456 extending along the cleat 454. Each shelf accommodates six boxes, three for the gun at one side, the belt-sections B in each set of three boxes being linked together and forming a continuous belt. The belt from each of the outer boxes is led up over a roll 457 and a guide-chute 458, carried by one of the brackets 413 of the shelf 412 for the upper shelf 446 and by a separate bracket 459 for the lower shelf 448, through an opening 460 in the wall and down to the breech mechanism of the gun. Each of the chutes 458 is so curved, as it extends upwardly, that it arranges the cartridges, which are displaced by the inclination of the shelves and boxes, in positions parallel to the longitudinal axes of the guns G. The shelf 412 not only supports the segment 410, but also serves as a rest for the

second man and protects him from the cartridge-belts as they are drawn by the guns from the boxes. The feed-openings 460 for the upper and lower guns may be covered by hinged and latched doors 461 (Fig. 17), and like openings 460, through which the guns may be serviced, have an upper sliding door 463 and a lower hinged door 465, each provided with a latch.

As the supply in the outer box for any one of the guns becomes exhausted, the second man removes this box from the shelf and shifts the remaining two outwardly to fill the space. He then places a full box at the inner end of the set and links its belt-section to that of the box in advance of it. Since the boxes of each set are closely placed with respect to each other and to the adjacent wall 60, and the removal of the leading box may be difficult, means is preferably provided for applying a force to the front of the box to displace it rearwardly. Guided for movement fore and aft of each shelf is a slide 462 (Fig. 3), drawn normally forward by a tension-spring 464, and movable in the opposite direction by a depending finger-piece 466. The latter movement carries the end 468 of the slide, which is bent upwardly and then rearwardly, through an opening 470 in the cleat 454 opposite the outer box and against the forward box-wall. The second man, when he wishes to remove the empty box, may tip it forward sufficiently for the rear lower edge to clear the cleat 452 and then draw back the slide by the finger-piece, forcing the end 468 against the front of the box and shifting this back across the cleat to a position from which it may readily be taken. A supply of the ammunition-filled boxes is carried upon forwardly and upwardly inclined shelves 472 (Fig. 2) attached to the turret-walls at one side of and beneath the chair 260, and also upon a floor 474 extending across the bottom of the turret. Into the spaces from which the filled boxes are taken may go the empty boxes.

The operation of the turret may be briefly summarized as follows. It is assumed that the gunner and the second man in the turret are in their elevated scanning positions. Upon sighting a target, for example, an airplane, the gunner depresses the handle 204. His weight then lowers the slide 188 and the seat 190 which is locked by the projection 207 in gunfiring position in which the eyes of the gunner are opposite the sight S. If necessary, the gunner also adjusts the head rest 222. The second man drops from the seat 268 to his chair where he attends—during the gun firing—to the replenishing of the ammunition by replacing the emptied ammunition boxes on the shelves 446, 448 with full boxes and connecting the belt sections in the full boxes with the sections being supplied to the guns.

The gunner controls the movement of the turret, and thus of the guns, to direct the fire of the guns by appropriate movement of the handles 346, 346. Movement of the handles in a horizontal direction effects operation of the hydraulic motor 96 to rotate the pinion 80 and thus to turn the table 19 and the guns in azimuth. Vertical movement of the handles effects operation of the hydraulic motors 130 to rotate the tires 56, 56 and thus the drum to elevate or depress the guns. If a lead correction should be required, the second man adjusts the sight by manipulation of the rod 402.

The gunner's chair C and the head rest 222 disclosed herein are not claimed herein since they are claimed in my copending application

Serial No. 624,302, filed October 24, 1945, which is a division of the present application.

The sight adjusting means disclosed herein is not claimed herein since it is claimed in my copending application Serial No. 760,151, filed July 10, 1947, which is a division of the present application.

The gun-charging mechanism disclosed herein is not claimed herein since it is claimed in my copending application Serial No. 624,303, filed October 24, 1945, which is a division of the present application.

Having described my invention, what I claim as new and desire to secure by Letters Patent of the United States is:

1. In a turret for anti-aircraft guns, the combination with a base, of a ring fixed upon the base and provided with an upwardly extending flange within which a surface of the ring furnishes a track, a table, a drum rotatable upon the table, a plurality of brackets depending from the table, means for securing the brackets in different positions radially of the table, and frusto-conical rolls rotatable upon the brackets and revolvable along the track, said table being retained against lateral displacement by engagement of the larger ends of the rolls with the flange of the ring.
2. In a turret for anti-aircraft guns, the combination with a base, of a table rotatable upon the base, pairs of rolls rotatable upon the table about horizontal axes spaced from each other, the rolls of each pair also being spaced from each other, and a gun-carrying drum having spaced circumferential projections resting upon the pairs of rolls and being rotatable thereon, one only of said rolls being provided with a groove receiving one of the drum-projections.
3. In a turret for anti-aircraft guns, the combination with a base, of a table rotatable upon the base, spaced pairs of pedestals rising from opposite sides of the table, a shaft journaled in each pair of pedestals, a pair of rolls rotatable by each shaft, a gun-carrying drum resting upon the pairs of rolls at opposite sides of its periphery, and plates variable in position upon the pedestals, and means arranged to secure the plates in clamping engagement with the drum.
4. The combination with a base, of a table rotatable upon the base, spaced pairs of hollow pedestals rising from opposite sides of the table, a shaft journaled in each pair of pedestals, a pair of rolls rotatable by each shaft, a drum furnishing a gun-turret and resting upon the pairs of rolls at opposite sides of its periphery, a motor mounted in each pair of pedestals, gearing connecting the motors to the rolls, a motor mounted upon the table between the pedestals of a pair, and gearing connecting the last-mentioned motor to the base.
5. The combination with a base, of a table rotatable upon the base, pairs of rolls rotatable upon the table about horizontal axes spaced from each other, the rolls of each pair also being spaced from each other, a drum rotatably supported by the rolls and furnishing a gun-turret, motors mounted upon the table, gearing by which one of the motors may be connected to the base, gearing by which another of said motors may be connected to the drum-rolls, and bearings associated with said gears and arranged to receive a pinion-carrying shaft and to place the pinion on the shaft in mesh with the gearing of the corresponding motor to permit manual rotation of the table or drum.
6. In combination, a movable turret, a gun

mounted upon the turret, motors by which the turret is moved in azimuth and in elevation to direct the fire of the gun, controlling means including valve mechanism by which the azimuth and elevation motors are governed and grip mechanism movable in azimuth and in elevation through which the gunner may move the valve mechanism, a grip member extending from the controlling means to a point convenient for actuation by a second man in the turret and supported for movements corresponding to those of the gunner's grip mechanism, and means for connecting the grip member to move the controlling means.

7. In combination, a movable turret, a gun mounted upon the turret, motors by which the turret is moved in azimuth and in elevation to direct the fire of the gun, controlling means situated at the front of the turret and including valve mechanism by which the azimuth and elevation motors are governed and a primary controlling member movable by the gunner in azimuth and in elevation to move the valve, a secondary controlling member mounted upon the turret for movement in azimuth and in elevation and two members connecting the secondary controlling member to the controlling means to communicate respectively thereto the azimuth and elevational movements, and a grip member connected to the secondary controlling member and extending to a point convenient for actuation by a second man in the turret.

8. In combination, a movable turret, a gun mounted upon the turret, motors by which the turret is moved in azimuth and in elevation to direct the fire of the gun, controlling means situated at the front of the turret and including valve mechanism by which the azimuth and elevation motors are governed and a primary controlling member movable by the gunner in azimuth and in elevation to move the valve, a secondary controlling member mounted upon the turret for movement in azimuth and in elevation, means for communicating the movements of the secondary controlling member to the primary controlling member, a tertiary controlling member movable similarly to the secondary controlling member at one side thereof, means for communicating the movements of the tertiary controlling member to the secondary controlling member, and a rod extending rearwardly from the tertiary controlling member for manipulation by a second man in the turret.

9. In combination, a movable turret, a gun mounted upon the turret, motors by which the turret is moved in azimuth and in elevation to direct the fire of the gun, controlling means situated at the front of the turret and including valve mechanism by which the azimuth and elevation motors are governed and grip mechanism movable in azimuth and in elevation through which the gunner may move the valve mechanism, a member pivoted upon the turret to rock in elevation, a second member pivoted upon the

first to rock in azimuth, and means for communicating both rocking movements of the second member to the grip mechanism of the controlling means.

5 10. In combination, a movable turret, a gun mounted upon the turret, motors by which the turret is rotated in azimuth and in elevation to direct the fire of the gun, controlling means situated at the front of the turret and including valve mechanism by which the azimuth and elevation motors are governed and grip mechanism movable in azimuth and in elevation through which the gunner may move the valve mechanism, a shaft rotatable upon the turret adjacent to the controlling means, two members fixed to the shaft to rock therewith, a member pivoted upon each of said fixed members to rock longitudinally of the shaft, means for connecting the two members to move together, means for connecting one of the members to the controlling means to impart its movements thereto, and a grip member connected to the other member on the shaft.
